UNITED STATES PATENT OFFICE.

GEORGE W. HUGHEY, OF SPRINGFIELD, MISSOURI, ASSIGNOR OF ONE-HALF TO
JOSEPH O. HOWARD, OF EVANSTON, ILLINOIS.

TOY.

1,426,646.

Specification of Letters Patent. Patented Aug. 22, 1922.

Application filed October 20, 1919, Serial No. 331,935. Renewed January 11, 1922. Serial No. 528,564.

To all whom it may concern:

Be it known that I, GEORGE W. HUGHEY, a citizen of the United States, residing at Springfield, in the county of Greene and 5 State of Missouri, have invented new and useful Improvements in Toys, of which the following is a specification.

This invention relates to toys and has particular reference to that class of devices 10 known as bubble pipes.

It is the purpose of this invention to associate with the bowl of the pipe, a toy balloon adapted to be inflated by blowing through the stem of the pipe, a novel construction of means being employed for holding the balloon in position, and at the same time permitting the parts to be readily assembled or disassembled as the occasion may require.

20 In carrying out the invention I equip the balloon with an attachment whereby a whistling noise is produced when the air is discharged from the balloon, thus providing a toy which will be exceedingly amusing 25 to young folks.

The nature and advantages of the invention will be better understood when the following detail description is taken in connection with the accompanying drawing, the 30 invention residing in the construction, combination and arrangement of parts as claimed.

In the drawing forming part of this specification, like numerals of reference indicate similar parts in the several views and 35 wherein:—

Figure 1 is a view showing the pipe in section and the balloon inflated.

Figure 2 is a sectional view through the 40 bowl of the pipe showing the balloon removed therefrom.

Figure 3 is a view of the separate elements of the balloon attaching means.

Figure 4 is a view of the balloon.

45 Referring to the drawing in detail, it will be noted that the toy comprises two essential parts, a pipe and a balloon. The bowl of the pipe is indicated at 10, and may be an integral part of the stem 11, or the stem 50 may be separable from the bowl as shown. The balloon is indicated at 12 and is provided with the usual neck portion 13 which is adapted to receive a short stem 14 illus-

trated in Figure 3. This stem is provided with a longitudinal bore, and is also formed 55 with an annular groove 15 adjacent one end, the ring-like extremity 16 of the balloon neck being adapted to be received within the groove 15 whereby the balloon and the stem are held associated. For the purpose 60 of associating the balloon with the bowl of the pipe, I make use of a disk 17 having a central opening 18 in which the stem 14 is fitted. The opening 18 is of a size to snugly receive the stem 14, while the diameter of the disk 17 may be such as to be frictionally maintained within the bowl of the pipe. If desired, the bowl of the pipe may be formed with an internal shoulder 19 upon which the disk 15 rests. A strip 20 of 70 suitable material is extended across the open end of the stem 14 and is secured to the stem in any suitable manner, this strip providing for a whistling noise when the air passes from the balloon through the stem 75 when the balloon is being deflated.

In use, the child blows through the stem 11, of the pipe, thus inflating the balloon 12, the latter resembling a bubble similar to those produced by the well known bubble 80 pipe. The balloon is associated with the bowl of the pipe in a manner to remain in position irrespective of what position the pipe is held, and at the same time the balloon may be readily disassembled or assembled 85 with the pipe as the occasion may require. When the air is allowed to escape from the balloon, it passes through the stem 14 thus producing a whistling sound with the assistance of the strip 20, a fact 90 which renders the toy particularly amusing to the young folks.

While I have shown and described what I consider the preferred embodiment of the invention, I desire to have it understood 95 that I do not limit myself in this connection, and that such changes may be resorted to when desired as fall within the scope of what is claimed.

What I claim is:—

100 In combination, a pipe comprising a bowl and a stem, an internal annular shoulder formed in the bowl of the pipe a slight distance above the lower end thereof, a disk 105 resting upon said shoulder and having a central opening, a tubular member passed

through said opening and frictionally held therein with its terminals disposed above and below the disk, said tubular member being open at both ends, that portion of the member arranged above the disk being formed with an annular groove, a balloon having a neck portion received by said

groove and adapted to be inflated by blowing through the stem of the pipe, and a strip extending across the lower end of the member to produce a whistling sound when the balloon is deflated.

In testimony whereof I affix my signature.

GEORGE W. HUGHEY.
